METHOD AND MEANS FOR IMPROVING THE UTILIZATION OF VOLATILE REFRIGERANTS IN HEAT EXCHANGERS

Charles E. Lowe, Orlando, Fla.

Application April 1, 1954, Serial No. 420,395

11 Claims. (Cl. 62—115)

The present invention relates to heat exchange systems employing a volatile refrigerant liquid and which may be used for the heating or cooling of water, air, or of other gases or liquids, as in heat-pumps, refrigeration, air-conditioning or ice-making apparatus or the like, and is concerned more particularly with the more efficacious employment of the refrigerant in an evaporator or work-performing heat exchange instrumentality. This application is a continuation-in-part of my co-pending application, Serial No. 314,364, filed October 11, 1952.

Heretofore, and so far as is known, in systems employing heat exchangers of the evaporator type—into which a volatile refrigerant is discharged for contact with tubes, coils or other surfaces to effect a heat-exchange therebetween and thus vaporize the refrigerant into a low-pressure fluid—the normal charge of refrigerant is such as to substantially flood the evaporator or to have a substantially large quantity of the liquid refrigerant retained in the bottom portion of the evaporator during the operational cycle. This has resulted in very slow and sluggish vaporization of the refrigerant with an accompanied inefficiency in the output of the heat exchanger unit.

Attempts have been made to overcome this situation by introducing the liquid refrigerant at the sides or at the top of the evaporator or by the employment of baffles to guide and direct the refrigerant—all for the purpose of causing the liquid refrigerant to flow over the surfaces of the evaporator to better absorb the heat therefrom and to vaporize. Another such attempt has been to introduce a portion of the high-pressure liquid refrigerant through jets and/or injectors into an evaporator flooded with low pressure or expanded liquid refrigerant for the purpose of creating a circulating movement of the liquid refrigerant within the evaporator, as in United States patents to Phillips No. 2,123,021 or to Boileau No. 2,132,932. These attempts to improve vaporization of the liquid refrigerant in, so-called, flooded systems could have theoretically some beneficial results in given circumstances, but, so far as I know, they are not employed. Further, it has been proposed to by-pass a portion of the high-pressure gaseous refrigerant from the compressor of the system to act as the impellant for aspirating low-pressure or expanded liquid refrigerant in an evaporator, as in United States Patent No. 2,159,251, thus "short-cycling" part of the capacity of the compressor or other refrigerant pump.

Furthermore, prior to my invention, heating and cooling systems of the reversible type, wherein there is a heat-exchanger that serves as a condenser on the cooling cycle and as an evaporator on the heating cycle, the charge of refrigerant in the system is controlled by that required for the cooling cycle and which, usually is more than required for the heating cycle. Nevertheless, during the heating cycle in such a system, the greater portion of liquid refrigerant, discharged into the evaporator (usually through an expansion valve), does not quickly vaporize but flows into and remains on the bottom of the evaporator and is not sufficient in volume to properly flood or contact the heating surfaces of the evaporator so as to be

5

10

vaporized to best advantage, thus resulting in slow and inefficient vaporization. To increase the amount of the refrigerant charge above that required or permissible for the cooling cycle in such systems of a given size or rating, to partially overcome the condition just mentioned, would raise the head pressure in the system to a point that would be dangerous and damage the system or would cause the safety devices to shut-off and open with such frequency that the efficiency of both the cooling and heating cycles would be of little or no utility.

Also, in some systems, where water tubes or coils are disposed within the evaporators, the water flowing in said tubes or coils freezes causing inefficient operation or a "shut-down" of the system until the condition is remedied or, should the tubes break or rupture, allowing the water to flow into the conduits for the refrigerant and hence damaging the system.

I have found that superior results are obtained, in any given case, at much less cost and with a smaller evaporator by introducing only high-pressure liquid refrigerant into a non-flooded evaporator, by means of an atomizing injector or aspirator pump, which also functions as a restrictor to nebulize the high-pressure liquid refrigerant, so introduced, thus eliminating the use of a conventional expansion-valve; the need of bleeding the system at any point to provide an impellant agent for an aspirator and/or the need of high-pressure and/or low-pressure floats for maintaining a desired liquid level in the evaporator or to serve as an expansion valve. By continuous nebulization of the high-pressure liquid refrigerant, during the cycle of operation, a mist is produced which substantially fills the evaporator and contacts and bathes all the surfaces of the evaporator, thus vaporizing quickly and passing from the evaporator to the suction side of the compressor (or its equivalent) as a low pressure gas; and any of the nebulized refrigerant that is not vaporized may be renebulized with the injected on-coming charge of high-pressure liquid refrigerant. In practice I have found that the amount of unvaporized refrigerant is relatively small during the cycle of operation and that I need to use only about 30% of the normal charge of liquid refrigerant employed in a flooded type evaporator or "chiller" and approximately 50% employed in the, so-called, dry expansion chillers (now most generally in use) with a much smaller evaporator for a given work-load, resulting in a more rapid response from the system and a greater work output at less cost than heretofore.

The object of the present invention, therefore, is to render evaporator units, when used as a "chiller" or in heat exchange systems of a "heat-pump" or the like, more efficient than heretofore obtainable by substantially increasing the output of a given system and, in some systems, the same result is obtainable with a liquid refrigerant charge substantially less than that previously regarded a normal charge for such system.

Another object of the invention is to provide an improved injector nozzle which has an accelerated pick-up of the liquid being injected or pumped thereby.

A still further object of the invention is the provision of an improved type of heat exchanger which may be used either as a condenser or vaporizer, which is not susceptible of being ruptured, by freezing, with all of the attendant disadvantages known in the art as a result thereof and which is relatively inexpensive to manufacture.

The objects of the present invention may be attained in a very inexpensive and practical manner by providing one or more injector (aspirator-pump) nozzles in the bottom of a non-flooded chambered evaporator and through which the liquefied refrigerant is introduced into the evaporator at substantially condenser pressure, the type of nozzle being such as to function as a restrictor to expand and nebulize the liquid emitted therefrom and as

40

45

50

55

60

65

70

an aspirator-pump. The bottom of the evaporator may be (and preferably is) provided with one or more sumps into each of which an injector nozzle is operatively disposed. The nozzle is so placed—or, when more than one is employed, are spaced along the said bottom—to cause the nebulized refrigerant to fill the entire vaporizer and absorb the heat from the surfaces thereof, thus vaporizing the refrigerant very rapidly which vapor passes from the evaporator. Such small portion of nebulized liquid refrigerant, that has not been vaporized, drops to the bottom of the evaporator and flows to the sump where it is picked-up by such injector nozzle or nozzles and again entrained and nebulized thereby with the on-coming high-pressure liquid refrigerant in a continuing cycle with the result that very little liquid refrigerant remains on the bottom of the vaporizer at any one time, i. e., often less than two inches in depth. It is preferred for efficient operation that the discharge end of the nozzle project, at least, slightly above the normal liquid refrigerant lever in the evaporator.

While this nebulization of the liquid refrigerant may be accomplished with any suitable chambered evaporator, it is preferred to employ a novel type of vaporizer consisting of a vertically disposed casing having greater height and width than depth, over the exterior surfaces of which flows a heat-bearing or a cooling liquid (as the case may require); and that the interior and exterior surfaces of the evaporator be provided preferably with vertically disposed fins to more quickly effect the heat exchange, the bottom wall of casing having one or more of my improved injector nozzles disposed in and supported thereby to direct the emitted liquid refrigerant introduced into the casing upwardly thereof, and there being a vapor "take-off" in the casing above said nozzles.

Other objects and advantages of the present invention will be apparent as the detailed description of this invention proceeds.

In the drawings, which illustrate several adaptations of the inventions as now devised and used,

Figure 1 is a schematic illustration of a system for heating water employing my invention;

Figure 2 is a schematic illustration of a system for cooling water employing my invention;

Figure 6 is a section of the improved evaporator equipped with the improved injector nozzle and taken substantially on line 6—6 of Figure 4;

Figure 7 is a fragmentary transverse sectional view of the improved evaporator and taken substantially on line 7—7 of Figure 6;

Figure 8 is a side elevation of a modified type of heat-exchanger embodying the present invention;

Figure 9 is a transverse sectional view taken substantially on line 9—9 of Figure 8; and

Figure 10 is a perspective view of an improved heat exchanger which may form or be inserted in a wall of a room or of a refrigerator.

Throughout the specification and drawings similar characters of reference refer to similar and like parts; and, as can be observed, the drawings show the improvements of this invention in several adaptations to illustrate the principles thereof.

Figures 1 and 2 illustrate very simple systems employing the improvements of this invention and each system comprises a condenser and an evaporator, as at 11 and 12

and at 11^a and 12^a respectively, interconnected by suitable tubing or pipe with a compressor, or its equivalent, as at 13 and 13^a respectively in a conventional manner but without the interposition of the conventional expansion valve between the condenser and the evaporator, the system shown in Figure 1 being arranged to function as a "heat-pump" and the system shown in Figure 2 being arranged to function as a cooling or freezing unit.

While the condensers and evaporators are shown in Figures 1 and 2 as being in accordance with the improvements of this invention, it is obvious that they be of any other operable type, provided, that with respect to carrying-out the nebulization of the volatile refrigerant liquid, the evaporator should be of hollow chamber type having heat-bearing surfaces associated therewith and into which evaporator the high pressure liquefied refrigerant is discharged, through an injector nozzle X, to produce an agitated mist or spray that fills the evaporator and continuously bathes the heat-bearing surfaces of said evaporator. Since the evaporator chamber will be under much less pressure than the entering refrigerant, the nebulized refrigerant, due to its expansion, is distributed throughout the evaporator chamber in a continuous movement over its interior surfaces and will more quickly and efficiently collect the heat from the said heat-bearing surfaces of the evaporator, thus vaporizing or gasifying rapidly, and will be drawn as a low-pressure gas to the suction side of the compressor or its equivalent. Should any of the nebulized refrigerant accumulate within the evaporator in liquid form, it is entrained by the injector nozzle X with the on-coming charge passing therethrough and be renebulized thereby, thus maintaining substantially all the liquid refrigerant within the evaporator, during the cycle of operation, in a finely divided and agitated state.

With particular reference to the "heat-pump" shown in Fig. 1, the compressor 13, when operated, circulates the refrigerant in the system in the direction of the arrows, drawing into it the low pressure gaseous refrigerant within the evaporator 12 through a return conduit 14 and discharging it, as a hot high pressure gas, into an outlet conduit 15 through which it flows to the condenser 11 where said gaseous refrigerant is liquefied. This high pressure liquefied refrigerant then passes from the condenser 11 through a conduit 16 to the evaporator 12 into which the liquid refrigerant is nebulized, through an aspirator or injector nozzle X under the condenser pressure, to fill the evaporator with a mist or fine spray that impinges upon and bathes all the surfaces of the evaporator. This nebulization of the liquid refrigerant causes quick and speedy vaporization of the refrigerant, which vapor or gas is drawn by the compressor 13 thereinto through conduit 14 and is again compressed in a continuous cycle. The heat-pump of Fig. 1 derives its heat from the condenser 11, which may be of the radiation or air cooled-type 20^b and 11^c shown in Figures 3 and 4, respectively, but is here shown as a water cooled type wherein the cooling water is sprayed or flows from a distributor head 17 and, by passing over the condenser 11, quickly absorbs the heat from the hot gases therein, the hot water being collected in a tank or receiver 18 from which it is circulated, as by a pump 19, through a heating-system, containing a radiator or radiators or other utilitarian unit, generally indicated at 20, which dissipates the heat from the water, or may be drawn from the unit 20 as hot water. The unit 20 may be connected with the distributor-head 17 to deliver cooled water to the condenser. A replenishing or "make-up" water line may be connected, as at 21, to the tank 18. A distributor head 22, similar to the head 17, is arranged over the evaporator 12 and connected to a suitable source of a heat-bearing transfer agent of supply, such as water for one example. A collector tank 23 underlies the evaporator 12 to receive the transfer agent that has flowed over the evaporator. The tank 23 may be connected to a waste-pipe or the transfer agent

therein may be recirculated to the head 22 after its temperature has been permitted to rise for its functional purposes, as by being circulated in pipes subjected to an ambient air or buried in the earth for two examples.

Figure 2 discloses a system similar to that shown in Fig. 1 with the same parts rearranged to function as cooling apparatus, said parts being designated by the same reference numerals as in Fig. 1 but raised by the exponent a. It will be observed that the circulating system for the heat transfer agent, which includes the parts 17^a, 18^a, 19^a and 20^a, is arranged in association with the evaporator 12^a instead of being associated with the condenser 11^a as in Figure 1; and the distributing head 22^a and the collector tank 23^a are arranged in association with the condenser 11^a instead of being associated with the evaporator 12^a, as in Figure 1. With this arrangement, it is clear that a heat transfer agent or medium, discharged from the distributing head 17^a and flowing over the evaporator 12^a, is cooled and delivered to the radiator or other cooling unit or device 20^a and is returned to the distributor head 17^a at a higher temperature.

The nebulization of the refrigerant may be employed in heating and cooling systems of the more conventional type shown in Figure 3 as a reversible cycle system. Such conventional reversible-cycle heating and cooling system generally comprises a compressor 13^b having its intake and discharge sides connected with a conventional reverse-cycle valve 24 controlled by a suitable actuator, indicated at 25, and which actuator may, in turn, be thermostatically and/or manually controlled in any well known manner now commonly practiced. The reverse-cycle valve 24 is connected by a conduit 14^b to a heat exchanger 11^b—12^b, which alternately serves as a condenser and evaporator, and is here shown as the conventional cylindrical type heat exchanger having internal water tubes 26 connected with and controlled by a conventional supply means indicated at 26^a. The reverse-cycle valve 24 is also connected by a conduit 15^b with a radiator 20^b through which ambient air may be forced by a fan 27. In accordance with the present improvement, the bottom wall b of the heat exchanger is provided with one or more injector nozzles X, as previously explained, and connected with the radiator 20^b by conduit 16^b. This conduit connection 16^b may have included therein, adjacent the radiator 20^b, a conventional expansion valve 28 which discharges into a distributing head 29 from which the expanded refrigerant passes through tubes 29^a to the radiator 20^b. Of course, it is understood that other types of heat exchangers may be employed instead of the radiator 20^b; but where an expansion valve 28 is employed the conduit 16^b is provided with a by-pass tube p to by-pass the expansion valve 28. The by-pass tube p is provided with a check valve v positioned to close against the flow of the refrigerant from the exchanger 11^b—12^b to the expansion valve 28 and to open when the flow of the refrigerant is from the radiator 20^b through the conduit 16^b to the heat-exchanger 11^b—12^b.

The arrangement shown in Figure 3, when functioning as a heat pump system, is such that the reverse-cycle valve 24 will be actuated to allow the refrigerant to pass from the discharge side d of the compressor 13^b, as a hot high pressure gas, into the pipe 15^b and flow directly to the radiator 20^b, it being noted that the expansion valve 28 is now closed or inactive due to the provision of the usual equalizer tube 28^a and the feeler-bulb 28^b connected, respectively, with the radiator 20^b and the conduit 15^b (which is now the hot high pressure gas line). Cooler ambient air, or returned air from the system, is drawn or forced by the fan through the radiator 20^b and is heated by extracting the heat from the gases in said radiator, which now acts as a condenser and liquefies the refrigerant therein as a high-pressure liquid. The refrigerant flows, as a high pressure condensed liquid, from the radiator 20^b through the tubes 29^a, distributing head 29, by-pass p and conduit 16^b to the in-

spirator or injector nozzle or nozzles X in the bottom b of the heat exchanger 11^b—12^b and is nebulized therein in the manner indicated by the arrows and as previously explained, forming a low pressure gas which is drawn by the suction side of the compressor 13^b through the tube 14^b back into the compressor in a continuous flow. The injector nozzles X, in Figure 3, may be inserted directly into the bottom b of the heat exchanger 11^b—12^b or the heat exchanger may be provided on its bottom with a plurality of sumps as shown in Figure 5.

When the valve 24 is actuated to reverse the cycle of the system to function for cooling, the hot compressed refrigerant gas, discharged from the compressor 13^b at d, is delivered through the conduit 14^b to the heat exchanger 11^b—12^b and passes over, or otherwise contacts, the tubes 26, thus liquifying the hot gas.

The liquified refrigerant drops to the bottom of the heat exchanger 11^b—12^b and passes, as a high pressure liquid, through the nozzles X in the bottom thereof and 20 through the conduit 16^b to the expansion valve 28 where the liquid refrigerant is discharged into a distributing head or drum 29 and, thence, through the tubes 29^a into individual portions of a coil or radiator 20^b. Air passing through the radiator, by means of the fan 27, is chilled; 25 and the refrigerant, absorbing the heat from the air, is converted into a low pressure gas and returns to the suction side s of the compressor 13^b through the conduit 15^b.

From the disclosure thus far it will be manifest that 30 the nebulization of the liquid refrigerant may be accomplished in any suitable type of chambered heat exchanger by means of one or more injector nozzles X, shown in Figure 5, threaded in the bottom side of the heat exchanger, or said nozzle may be welded or soldered in 35 position. It will be manifest also that, should the nozzles X in any given case be found too restrictive of the flow of the condensed refrigerant when passing from the heat-exchanger, such as 11^b—12^b, to the heat-exchanger 20^b in Figure 3, when the system is functioning for cooling 40 purposes, a by-pass, provided with a one-way check valve, similar to by-pass p, may be employed between the interior of the heat-exchanger 11^b—12^b and conduit 16^a to permit the free flow of the high-pressure condensed refrigerant to the conduit 16^b, but which will close to 45 the passage of high-pressure liquefied refrigerant from the conduit 16^b to the heat-exchanger 11^b—12^b and, thus direct such passage of the high-pressure condensed refrigerant entirely through the nozzles X at condenser pressure.

As many of such nozzles X may be employed in spaced 50 relation along the bottom of the evaporator as may be found sufficient to fill the same with the nebulized refrigerant, according to its size or capacity, and which, during the injecting operation, will maintain the un-vaporized liquid refrigerant—that may drop to and accumulate on the bottom of the evaporator—to a point just above the injector passages 36 of the nozzle X and below its discharge orifice 35^b (see Fig. 5), or to cover 55 said orifice in some other types of injector nozzles which may be employed and which have to be primed to start the injecting operation. The exterior ends of the nozzle or nozzles X or are connected to a supply conduit, such as 16, 16^a or 16^b. It is preferred that the nozzles X be disposed in sumps 38 formed in a bottom wall b of the evaporator, as shown particularly in Figure 5. Each 60 sump is dimensioned so that the accumulated liquid will drain and collect therein and that the top of the sump is, at least, above the injector passages 36 of the injector nozzle and it is preferred that the discharge orifice 35^b of the injector nozzles X project above their sumps 38 and above the normal liquid level in the evaporator.

The injector nozzle X, shown in Figure 5, is of my 65 improved construction which gives extremely quick acceleration and force in injecting or entraining the liquid refrigerant in the bottom of the heat-exchanger. My 70

injector nozzle comprises the usual impeller jet nozzle 30 projecting from one end of a threaded boss 31 having a wrench-head 32 on its other end. The jet nozzle 30 is conical externally and internally terminating in an axially disposed discharge opening 30^a and communicating at its base with a passage 33 in said boss and wrench-head 32. The passage 33 is internally threaded to receive the threaded end of the conduit tube, such as 16, 16^a or 16^b. Surrounding the impeller jet nozzle 30 is a sleeve 34 which has its inner end suitably secured to the boss 31 in any suitable manner, soldering being shown. The interior of the sleeve 34 is formed to provide a Venturi throat 35 at a distance beyond the discharge opening 30^a of the impeller jet, this throat being preferably formed by having its inner portion 35^a conical and spaced from the exterior conical surface of the impeller jet 30 and converging to the throat 35 and by having its outer portion 35^b formed with a conical surface diverging from said throat 35 to provide the discharge orifice 35^b. The cross-sectional area of the throat 35 should be in the order of about twice that of the cross-sectional area of the impeller jet opening 30^a.

Injector passages 36 are provided in the sleeve 34 to communicate the exterior of the sleeve with the interior thereof and are positioned at a point in the sleeve between its inner end and the impeller-jet opening 30^a, these passages being preferably circumferentially about the sleeve. The injector passages 36 may be of any configuration or dimension, but it is preferred that they compose a circumferential series of passages of about $\frac{1}{32}$ inch in diameter to form strainer screen to exclude sediment or any foreign matter larger than the throat 35 from passing into the injector nozzle, the total opening area of the passages 36 being in excess of the space area between the inner surface of the sleeve 34 and the jet nozzle 30 at the point where they oppose, and, preferably, not less than 3:1 with respect to the narrowest cross-sectional area of the throat 35, thus providing adequate admission of the liquid to be injected or pumped. The nozzles X may be periodically cleaned by merely unscrewing them; however, in practice it has been found that this screen is an over-precaution and seldom needs to be cleaned.

The injecting action of the injector nozzle X is materially enhanced by the provision of an interceptor bar or baffle 37 extending transversely across the passage of the impeller-jet 30 at a point substantially inwardly of and aligned athwart its orifice 30^a, as shown in Figure 5 of the drawings. This transverse baffle 37 consists of a bar or rod having its ends swaged or soldered in suitable openings drilled in the nozzle wall. The surface of the bar opposing the flow of the impeller liquid through the jet 30 is flat, as shown at 37^a in Fig. 5, and is of a width to obstruct about one-third of the area of the passage in the jet nozzle 30 at the point where the bar is positioned. The back surface of the bar 37 may be rounded, as shown. From practical operation, it has been found that by the employment of the bar 37 with the flat surface 37^a, the injecting action of the nozzle X has been greatly increased by the propelling action of the impelling refrigerant emitted from the impeller jet 30 and creates such a suction or impelling-action on the fluid, being injected through the injector-passages 36, that the injection action can be started without priming or the liquid covering the top of the injector-nozzle so long as the liquid merely covers the injector passages 36. In the use of my injector nozzle X constructed as above, with the jet discharge opening 30^a of $\frac{1}{16}$ inch in diameter and the throat 35 of $\frac{1}{8}$ inch in diameter and using water under 60 lbs. pressure, as the impeller liquid, the water has been ejected to a vertical height of about 42 feet while inspirating or injecting water through the passages 36.

The evaporators, shown in Figs. 1, 2, 4, 6, 7, 8, 9 and 10, are constructed, in accordance with my present improvement, to effect quick heat-exchange in connec-

tion with a nebulized volatile refrigerant and to prevent damage thereto, due to freezing of the heat-transfer agent or medium and/or its seepage into the system with the refrigerant due to rupture caused by said freezing. This improved heat-exchanger may serve either as an evaporator or as a condenser, as shown; but, when used as a condenser, it need not be equipped with the nozzle X except in a reversible system where the heat-exchanger acts alternately as condenser or an evaporator according to the direction of cycle of operation, as is well understood in the art.

The detailed construction of the heat-exchangers 11, 11^a, 12 and 12^a is more particularly shown in Figs. 6 and 7, and, in addition to its above mentioned advantages, 15 also may be employed as an ice-maker, as will be later described. These heat-exchangers comprise a vertically positioned and generally rectangular shaped casing C having a height and width greater than its thickness or depth. The casing is preferably constructed from sheet metal 20 with spaced and opposed side walls s, end wall e, bottom wall b and a top wall t. The dimensions of the casing C may be that designed for a required or given capacity. When the casing C is to be used as a heat-exchanger with a liquid heat-transfer agent or medium, such for instance as water, its side walls s converge upwardly, as shown, 25 so that the heat-transfer agent may flow downwardly and exteriorly of the casing C from an overlying source of supply. If the side walls s converge upwardly, as shown in Figs. 1, 2, 4, 6 and 7, as preferably for use with a liquid transfer medium, the top wall t may be omitted and the top edges of the side walls s may meet. When employed as an evaporator, the bottom wall b of the casing C is provided with one or more sumps 38 in which a nozzle X is disposed, as explained above.

The exterior, and preferably the interior, surfaces of the casing C are provided with fins f to accelerate the heat exchange. These fins, preferably formed of elongated strips of sheet metal, substantially right-angular in cross-section, are arranged vertically on said surfaces of the side walls s and end walls e extending from the top to the bottom thereof and lying in close relation with one of their angular portions flat against said walls and secured thereof by welding or soldering, thus reinforcing said walls.

In Figures 8 and 9 is shown a further extension of my improved evaporator C' which may be employed in any system having a pressure differential from a high to a low side and does not require internal circulating tubes therein, but may be submerged in a heat medium from 50 which heat may be extracted by conductivity or radiation and absorbed by the nebulized refrigerant or may be buried in the ground or otherwise placed in an appropriate location to absorb the heat from the surrounding environment.

The evaporator, shown in Figs. 8 and 9, comprises a rather narrow vertically elongated chamber C' having side walls 40, end walls 41, a top wall 42 and a bottom wall 43, all of heat conducting material. The chamber C' is preferably of less thickness than its height or width 55 and the side walls may be connected by stay-rods 44 to give rigidity to the same, if necessary. One or more injector nozzles X may extend into the bottom of the chamber C' through the bottom wall 43 to direct its spray upwardly into the chamber C' and connected (as described in connection with Figs. 1, 2 and 3) to a high pressure conduit 16, 16^a or 16^b, whereby the liquefied refrigerant will be nebulized by the injector nozzles X, as previously explained, until it has absorbed sufficient heat from the side walls of the chamber C' to gasify and 60 discharge from the chamber C' through conduit 14^c, as a low pressure gas. The charge of refrigerant required, with the heat exchanger C', may be only enough to keep the passages 36 in the injector nozzles X covered in normal operation, as indicated, thereby using less refrigerant 65 and functioning more effectively. Of course, fins f, shown 70

in Figs. 6 and 7, may be arranged within, as well as exteriorly of, the chamber C', if desired.

Figure 10 shows a further adaptation of my invention to an improved cooling unit C' that may be employed in or as the walls of a refrigerator or freezer or in or as panels in the walls of buildings and which does not require the use of expensive cooling coils or of a "so-called" "honey-comb" construction. This cooling unit, like the heat-exchanger shown in Figs. 6, 7, 8 and 9, comprising a rather narrow vertical disposed elongated chamber C' having side walls 50, end walls 51, a top wall 52 and a bottom wall 53, all of heat conducting material, and the side walls may be connected by stay-rods 54 to give strength and rigidity to the structure, if necessary. Baffles 55 are thermally connected to the walls of and suitably arranged in said chamber C' to deflect and transfer, one to the other, liquefied refrigerant emitted into the top of said chamber and to direct it downwardly to the bottom of said chamber. One or more injector nozzles X may extend into the chamber C' through the bottom wall 53 and connected to conduit 16^d supplying a high pressure liquified refrigerant thereto. Connected to each injector nozzle X is a vertical pipe 57 extending to the top of the chamber C' and provided with a downwardly direct discharge end 57^a, whereby the nebulized refrigerant showers downwardly of said chamber and is intercepted by said baffles 55, thus absorbing the heat from the walls of said chamber. Any refrigerant that is vaporized by this action passes as low pressure gas back to the compressor, or the like, through pipes 14^d as shown in Figs. 1 and 2; but such of the refrigerant which is not vaporized falls into the bottom of the chamber C' and is again picked-up (as previously explained) by injection through passages 36 in said injector-nozzles X and redischarged at 57^a until it has absorbed sufficient heat to gasify and discharge from the chamber C' through low pressure conduit 14^a. If desired, the exterior surfaces of the side walls 50 may be provided with fins f as shown in Figs. 6 and 7.

Further utilization of the improvements of my invention is shown in Figures 4 and 6, wherein there is disclosed a novel system for making ice and/or chilling water for commercial purposes. This novel system is preferably of the reversible cycle type similar to that shown in Figure 3 and may comprise a compressor or equivalent 13^e, a reverse-cycle valve 24^e, a condenser 11^e, an evaporator 12^e—all conveniently arranged and interconnected in the usual manner. The condenser 11^e may be of any desired or convenient type, but is here shown as an air cooled type. The evaporator 12^e is of the type, hereinbefore described in connection with Figs. 1, 2, 6 and 7, comprising a vertically disposed hollow casing having bottom wall b, upwardly converging side wall s and relatively narrower end walls e, the bottom b having one or more sumps 38 therein, in which are mounted injector nozzles X preferably of my improved type above described. A water distributor head 22^e is arranged and supported over the apex of the side-walls s to direct a water spray downwardly onto the declining surfaces thereof. The distributor head 22^e is supplied from a suitable source, which may be an open tank 23^e disposed under the evaporator 12^e to catch water that may flow therefrom. The tank 23^e may be supplied by a feedpipe 21^e controlled by a water-level means 39; and the water from the tank 23^e may be pumped therefrom to said distributor head 22^e by a pump 19^e. With this arrangement, water discharged from the distributor head 22^e flows over the exterior surfaces of the side walls s of the evaporator 12^e and is caused to freeze thereon, during the nebulization therein of the high pressure liquified refrigerant flowing thereto through pipe 16^e from the condenser 11^e, which, in turn, receives hot refrigerant gas through pipe 15^e from the discharge side of the compressor 13^e. The gradual freezing of said water flowing from the head 22^e will increase the thickness of the ice

sheet to a permissible or desired degree, any excess water flowing into the tank 23^e for recirculation. When the desired thickness of ice has formed on the walls of the evaporator 12^e, the reverse-cycle valve 24^e may be manually actuated, or may be automatically actuated by a control means 25, shown in Fig. 3 or other equivalent means, which in turn is preferably actuated by a timing device or thermostat not shown, to cause the hot refrigerant gas, from the compressor 13^e, to flow directly into the evaporator 12^e by means of pipe 14^e, where the heat of said gas causes the ice adhering to the surfaces of the evaporator to drop therefrom into a bin 60. The bottom of the bin may have a conveyor belt 61 therein to move the ice therefrom. After a predetermined time lapse, the control means 25^e is again actuated, either by said timing means or by a thermostat 62, to operate reverse-cycle valve 24^e to reverse the operation of the system to repeat its cooling or freezing operation, just described, until the machine is shut-down or stopped. Of course, it is understood from the foregoing description that, after the hot refrigerant gas enters the evaporator 12^e from pipe 14^e during the heating cycle, it liquifies and returns to the condenser 11^e through pipe 16^e where it vaporizes and passes to the suction side of the compressor 13^e. The fins f, on the exterior surface of the evaporator 12^e, will cause the ice to form much more rapidly and in long and narrow strips that are easily handled and may be easily broken to desired lengths or crushed.

The apparatus shown and described in connection with Fig. 4 may also be economically employed for chilling water for commercial or industrial purposes and, to this end, the cold water flowing down the side-walls s of the evaporator may be collected in the tank 23^e and the distributor head may be connected directly to the supply pipe 21^e, the pump 19^e being employed to discharge the cold water to a service system, and, in such case, the water-level control valve 39 may not be used.

Having thus described my invention and the several manners in which the same may be performed, it will be seen that the objects thereof are attained by the constructions therein disclosed; but, since the said constructions are susceptible to modifications and variations (some of which being stated and others being obvious after stating my invention), it is to be understood that the invention herein described is to be limited only by the scope of the appended claims.

That which is claimed as new and to be secured by Letters Patent is:

1. As a method of more effectually utilizing a volatile liquified refrigerant in a circulating heat-exchange system having a condenser-means and an enclosed evaporator-chamber with heat-transfer surfaces; the steps of continuously passing to said chamber only the liquified refrigerant, coming from said condenser means, while under pressure from the condenser and discharging the same into said chamber, under said pressure, in a nebulized state causing all but a small percentage of said discharged refrigerant to flash and causing a non-flooded condition of said chamber, during the operation of the system; said discharge of the refrigerant into said chamber inspiring therewith any unvaporized refrigerant that has been previously discharged and collects in said chamber, as a liquid body, to renebulize the same; and drawing the vaporized or gasified refrigerant from said chamber into the system.
2. As a method of more effectually utilizing a volatile liquified refrigerant in a circulating heat-exchange system having a condenser means and an enclosed evaporator-chamber with heat-transfer surfaces; the steps of continuously injecting in a nebulized state all of the condensed liquified refrigerant, coming from the condenser means, directly into the non-flooded evaporator chamber and under condenser pressure, during the operation of the system, causing rapid gasification of said refrigerant; said injecting of said refrigerant in said chamber inspiring

therewith only the nebulized refrigerant that collects in the chamber, as a liquid body, to renebulize the same; and drawing the vaporized or gasified refrigerant from said chamber into the system.

3. In an apparatus employing a circulating refrigerant and which includes a system having a condenser means for converting the refrigerant, in its gaseous phase, to a high-pressure liquid and a heat-exchanger to gasify said high-pressure liquid; the improvement being that said heat-exchanger has an enclosed chamber therein connected in said system, one or more atomizing injector nozzles located in said chamber and connected directly to the condenser in said system to have all of the refrigerant from the condenser pass therethrough in its liquid phase and substantially under condenser pressure, during the operation of said system, whereby said liquefied refrigerant acts as a high-pressure liquid impellant pumping medium for said injector nozzle or nozzles, which latter nebulizes the liquefied refrigerant passing therethrough; the arrangement being such that the emitted nebulized liquid refrigerant impinges upon and contacts the interior surfaces within said chamber, effecting quick gasification of the refrigerant without flooding said chamber with a liquid body, and inspirates any ungassed low-pressure refrigerant, that accumulates in said chamber, with the on-coming high-pressure liquefied impellant refrigerant and re-nebulize the same, whereby said interior surfaces of said heat-exchanger may be repeated and continuously bathed by the nebulized liquefied refrigerant, during operation of the system, until gasified and drawn from said chamber, as a low pressure gas, to be again converted to a high-pressure gas.

4. An evaporator for a circulating volatile refrigerant system having a condenser means and a compressor means, said evaporator comprising a hollow body member forming a chamber having an outlet removed upwardly from the bottom thereof, an atomizing injector nozzle mounted in the bottom of said chamber for connection in a circulating system to receive liquefied refrigerant therefrom at substantially condenser pressure and to function as a restrictor and positioned to direct its emitted liquefied refrigerant upwardly to impinge upon the interior surfaces of said chamber in a finely divided state and pass through said outlet as a low pressure gas, said nozzle having an inspirator passage therein positioned to cause any ungassed refrigerant accumulating on the bottom of said chamber to be entrained with the high-pressure liquefied refrigerant, being introduced into said chamber, so as to be renebulized therewith, whereby said chamber is not flooded with a liquid body of said refrigerant and the surfaces of said chamber are continuously bathed with nebulized liquid refrigerant, while the system is in operation, until gasified and drawn from said chamber.

5. The subject-matter of claim 4 wherein said chamber has a sump in the bottom thereof into which liquid refrigerant on the bottom of said chamber flows, said nozzle being positioned in said sump and having the inspirator passage therein within and communicating with the sump, the discharge orifice of said nozzles projecting above said sump and above the normal level of any accumulated liquefied refrigerant in said chamber.

6. The subject-matter of claim 4 wherein said heat exchanger is a vertically disposed enclosed hollow casing of heat conducting material of greater height and width than thickness, the exterior walls of said heat exchanger being exposed to a heat-transfer medium.

7. The subject-matter of claim 4 wherein said heat exchanger is a vertically disposed enclosed hollow casing of heat conducting material having opposed downwardly diverging exterior side walls, and means arranged above said surfaces for discharging heat-transfer medium onto said side walls.

8. An evaporator, for use as a cooling wall panel with a cooling system employing a volatile refrigerant, said evaporator comprising a closed panel member of heat

conducting material having spaced vertical side walls forming a chamber therebetween, the exterior surfaces of said walls being adapted to be exposed to ambient air, one or more injector nozzles mounted in the bottom of said chamber and adapted to be connected to a source of liquefied refrigerant under pressure to provide the impellant pumping medium for said injector nozzles, a tube communicating said discharge end of said nozzles with the top of said chamber and emitting said injected refrigerant therefrom, and baffle means arranged in and thermally connected to said walls of said chamber to deflect and pass said refrigerant one to the other in its downward passage in said chamber, any liquefied refrigerant accumulating in the bottom of said chamber may be repeatedly inspirated by said nozzle or nozzles with the impelling medium upwardly in said tube and discharged therefrom until gasified, said chamber having a gas outlet therein adapted to be connected in the cooling system.

9. In combination with a reversible heat exchange system employing a volatile refrigerant, of a heat exchanger alternately acting as a condenser and as an evaporator upon reversed cycles of said system, said heat exchanger being a vertically disposed wall-enclosed chamber having two opposed sides converging upwardly from its bottom, a water spray device arranged to direct its spray onto the exterior surfaces of said inclined sides of said walls, atomizing injector nozzle means located in the bottom of said chamber and connected in said system with the high-pressure liquefied refrigerant and positioned to direct the nebulized refrigerant upwardly into said chamber to impinge the walls thereof, said nozzles having an inspirator passage therein adapted to be surrounded by liquefied refrigerant accumulating on the bottom of said chamber to reatomize the same with the oncoming pressure charge of the liquefied refrigerant, said chamber having an outlet therein removed upwardly from said nozzles and connected in said system to draw gasified refrigerant therefrom as a low pressure gas, whereby ice may be formed on said exterior inclined surfaces of said heat exchanger and may be released therefrom upon reversing the cycle of the system allowing said ice to move downwardly off said surfaces.

10. The subject matter of claim 9 wherein there is a collector to receive excess water flowing from said inclined surfaces of the heat exchanger and connected with the water supply to said spray device, and means for receiving and collecting the ice dropping from said heat exchanger.

11. A vaporizer for a circulating volatile refrigerant comprising a shell-like heat-exchanger in the form of a walled chamber of heat conducting material and devoid of fluid circulating tubes therein for a separate heat-exchange medium and having an inlet and an outlet for said refrigerant to pass thereto and therefrom, respectively, atomizing injector-nozzle means located in the bottom portion of said heat-exchanger to be surrounded by any liquefied refrigerant in the bottom of said heat-exchanger for aspirating said liquefied refrigerant and connected in a circulating system at the inlet of said heat-exchanger, said nozzle means being positioned to direct its emitted spray to impinge upon and contact the interior surfaces within said heat-exchanger, whereby said interior surfaces of said heat-exchanger may be repeatedly and continuously bathed by atomized refrigerant emitted from said nozzle means while the system is in operation until gasified or vaporized.
